MELVIN A. PENROD AND CHARLES A. BROOKS, OF SWISSVALE, PENNSYLVANIA, AS
SIGNORS TO THE UNION SWITCH & SIGNAL COMPANY, OF SWISSVALE, PENNSYLVANIA, A CORPORATION OF PENNSYLVANIA

RAILWAY SIGNALING SYSTEM

Application filed April 5, 1930. Serial No. 441,829.

Our invention relates to railway signaling systems of the type involving a switch and a signal governing traffic over such switch. One feature of our invention is the provision 5 of novel and improved means for automatically causing said signal to give progressive indications as a train passes progressive distances beyond the signal.

We will describe one form of signaling 10 system embodying our invention, and will then point out the novel features thereof in claims.

The accompanying drawing is a diagrammatic view showing one form of system embodying our invention.

Referring to the drawing, the reference characters 1 and 1^a designate the track rails of a stretch of main track N, which rails are divided by insulated joints 2 to form a 20 plurality of successive track sections of which only two sections A—B and B—C, are shown complete in the drawing. Located in the section A—B is a switch Q leading into a yard track Z. This yard track is provided with a track section D—E, the end D of which is located beyond the fouling point of the switch Q.

Traffic into the section A—B, and therefore through the switch Q, is governed by a 30 signal S. This signal comprises a main group of lamps V, and an auxiliary group of lamps W, each group comprising a green lamp G, a yellow lamp Y, and a red lamp R. The signal also is provided with a calling-on lamp Y¹. The indications given by the signal S will be explained during the explanation of the operation of the system as a whole.

The switch Q is actuated between normal and reverse positions by a switch mechanism 40 4, which in turn, is controlled by a manually operable lever P^q, located, for example, in the dispatcher's tower and having normal and reverse positions corresponding to those of the switch. This lever comprises a pair of pole-changing contacts 5 and 6, whereby current of normal polarity is supplied to the mechanism 4 from terminals *x* and *o* when the lever is in normal position, and a current of reverse polarity is supplied to the mechanism from these terminals when the lever is in the

reverse position. Lever P^q is also provided with additional contacts 7, 8, 24 and 37, the functions of which will be explained hereinafter.

The signal S is controlled in part by a manually operable lever P^s, also located in the dispatcher's tower and having a middle position and a right-hand position, which positions we will for convenience refer to as the normal and reverse positions respectively. 55 This lever is provided with a contact 9 which is open when the lever is in the normal position, and is closed when the lever is reversed. Associated with the lever P^s is a normally open push button 40 of the type which may be closed by hand, but which immediately returns to an open position as soon as it is released. That is to say, this push button is of the "non-stick" type.

Each track section is provided with a track 65 circuit comprising a battery 3, and a track relay designated by the reference character T with a distinguishing exponent.

The reference character U designates a repeater relay, which is controlled in part by the track relays and in part by the switch lever P^q. When the switch lever is in the normal position, the circuit for relay U is from terminal *x*, through front contact 11 of track relay T², contact 7 of switch lever P^q in 75 its left-hand position, front contact 12 of track relay T¹, and the winding of relay U to terminal *o*. It follows that with lever P^q in the normal position, relay U will be energized if, and only if, both track sections A—B 80 and B—C of the main track N are unoccupied. When lever P^q is reversed, the circuit for relay U is from terminal *x*, through front contact 10 of track relay T³, contact 8 in its right-hand position, front contact 12 of track 85 relay T¹, and the winding of relay U to terminal *o*. It follows that when lever P^q is reversed, relay U will be energized if and only if track sections A—B and D—E are unoccupied.

The reference character M designates a relay which is controlled in part by the track relays and by the switch lever P^q. There are two circuits for relay M. The first of these circuits is from terminal *x*, through back con- 90

tact 11 of track relay T^2 , contact 24 of lever P^q in its normal position, front contact 13 of track relay T^1 , and winding of relay U to terminal o . The second of these circuits is from terminal x , back contact 10 of track relay T^2 , contact 37 of lever P^q in its reverse position, front contact 13 of track T^1 , and winding of relay U to terminal o . It follows that with lever P^q in its normal position, relay U will be energized if, and only if, track section A—B is unoccupied and the track section B—C of main track N is occupied by a train, and that with the lever P^q in its reverse position, relay U will be energized if and only if track section A—B is unoccupied and track section D—E of yard track Z is occupied by a train.

Signal S is directly controlled by a distant relay F, a home relay H, a yard relay J, and a calling-on relay K. This signal is also controlled in part by a circuit controller L operatively connected with the switch Q, and comprising two contacts 17 and 19 closed when the switch occupies its normal position as shown in the drawing, and a contact 18 closed when the switch is reversed.

We will assume that all of the track sections A—B, B—C and D—E are unoccupied, that the switch Q, is in the normal position, and that the dispatcher desires to admit a train moving toward the right into section A—B. To do this, he will move the signal lever P^s to the right-hand or reverse position, thereby energizing relay H, the circuit being from terminal x , through contact 9 on lever P^s , front contact 15 of relay U, winding of relay H, and back contact 33 of calling-on relay K to terminal o . The circuit for the distant relay F includes the normally closed contact 19 of circuit controller L, as well as other controlling contacts to the right of section B—C, not shown in the drawing, and for present purposes we will assume that this relay is energized. Green lamp G in group V of signal S will then be lighted by a circuit which passes from terminal x , through front contact 22 of relay H, front point of contact 23 of relay F, and lamp G to terminal o . At the same time the lamp G in group W will be lighted by a circuit from terminal x , through front contact 21 of relay H and normally closed contact 17 of switch operated circuit controller L. Signal S will then give the proceed indication. If the distant relay F is deenergized, lamp G of group W will be lighted as before, but lamp Y instead of lamp G in this group V will be lighted, the circuit for lamp Y including the front contact 22 of relay H, and the back point of contact 23 of relay F. When the train enters section A—B, it will deenergize track relay T^1 , and this in turn will deenergize relay U, thereby opening the circuit for relay H at contact 15 of relay U. The two red lamps R of signal S will then be lighted.

by a circuit from terminal x , through back contact 25 of relay H, back contact 26 of relay J and the two red lamps R in multiple to terminal o . Signal S will then indicate "stop".

We will now assume that the train which occupies section A—B passes the point B, thereby causing the reenergization of track relay T^1 and the closing of its front contacts 12 and 13 and also causing the deenergization of track relay T^2 and the closing of its back contact 11. Relay U will continue to be deenergized because its circuit will now be open at contact 11 of track relay T^2 , but relay M will become energized because its circuit will be closed at both contacts 11 and 13. Relay J will then become energized by virtue of a circuit which passes from terminal x , through contact 9 of signal lever P^s , back contact 15 of relay U, front contact 16 of relay M, winding of yard relay J, and back contact 33 of calling-on relay K, to terminal o . The energization of yard relay J establishes a circuit from terminal x , through front contact 28 of relay J and lamp Y of the group V of lamps to terminal o and also a circuit from terminal x , through contact 29 of relay J, contact 17 of the switch operated circuit controller L and lamp G of the group W of lamps to terminal o . A circuit is also thus established from terminal x , through a front contact 30 of relay J and lamp Y^1 of signal S to terminal o . The signal is thereby caused to display what is known as a "yard" indication for the main track N, that is, it will indicate to the following train that the switch Q is normal, that the section A—B is unoccupied, but that the section B—C of the main track N is occupied.

If all three of the track sections are unoccupied and the switch Q is reversed, and the dispatcher moves the signal lever P^s to its reverse or right-hand position, relays U and H will become energized by virtue of the circuit previously traced through contacts 9, 15 and 33. This will result in the lighting of the lamps Y in groups V and W, the circuit for the former being from terminal x , through front contact 22 of relay H, back contact 23 of relay F, lamp Y of group V of lamps to terminal o , and the circuit for the latter being from terminal x through front contact 22 of relay H, back contact 27 of relay J, contact 18 of circuit controller L and lamp Y of group W of lamps to terminal o . This gives a "clear" indication for track Z.

We will now assume that switch Q is reversed, that section A—B is occupied by a train, and that the dispatcher desires to admit a second train into this section. Relay U will now be deenergized, because its circuit will be opened at contact 12 of track relay T^1 , and relay M will be deenergized because its circuit will be open at contact 13 of the same track relay. The dispatcher will then

- reverse the signal lever P^s and will also close the push button 40. The calling-on relay K will then become energized by virtue of a circuit which passes from terminal α , through contact 9 on the signal lever P^s , back contact 15 of relay U, back contact 16 of relay M, push button 40, and winding of calling-on relay K to terminal α . When the relay K becomes energized, lamp Y^1 of signal S will become lighted by virtue of a circuit which passes from terminal α , through front point of contact 31 of relay K and the lamp Y^1 of signal S to terminal α , thereby causing the calling-on indication to be displayed.
- 15 The energization of relay K also closes a front contact 32 which immediately establishes a stick circuit for this relay from terminal α and contacts 9, 15, 16 and 32 and winding of relay K to terminal α . This stick circuit maintains the relay K energized after the dispatcher releases the push button 40 which, as has been pointed out, is of the non-stick type.
- 20 We will now assume that before the calling-on indication is accepted by a following train, the train which occupies section A—B passes the point D, thereby causing the reenergization of track relay T^1 and the closing of its front contacts 12 and 13 and also causing the deenergization of track relay T^2 and the closing of its back contact 10. Under these conditions relay U will continue to be deenergized because its circuit will now be open at contact 10 of track relay T^2 , but relay
- 25 M will become energized because its circuit will be closed at both contacts 10 and 13. Relay J will then become energized by virtue of the circuit previously traced through the contacts 9, 15, 16 and 33, and reestablish the circuit for the lamp Y of the group V of lamps previously traced through the contact 28 of this relay, and also a circuit from terminal α , through contact 27 of relay J, contact 18 of the switch operated circuit controller L and lamp Y of the group W of lamps to terminal α . The energization of relay J also reestablishes the circuit for the lamp Y^1 of signal S previously traced through contact 30 of this relay. The signal S is
- 30 thereby caused to display what is known as a "yard" indication for the track Z, that is, it will indicate to the following train that the switch Q is reversed, that the section A—B is unoccupied, but that the section D—E of the
- 35 yard track Z is occupied. It will be observed that this transfer from relay K to relay J is entirely automatic, and does not require manual operation of the push button 40.
- 40 Signal S can be caused to give other indications than those specifically referred to, but such other indications have nothing to do with our present invention, and consequently, it is not necessary to explain them in detail.
- 45 Although we have herein shown and described only one form of signaling system

embedding our invention, it is understood that various changes and modifications may be made therein within the scope of the appended claims without departing from the spirit and scope of our invention.

Having thus described our invention, what we claim is:

1. In combination, a stretch of railway track divided to form a section, a signal governing traffic into said section and capable of displaying a calling-on and a yard indication, manually controlled means for causing said signal to display a calling-on indication when said section is occupied by a train, and means operating automatically for causing said signal to display a yard indication when such train leaves said section. 70
2. In combination, a stretch of railway track divided to form a first and a second section, a signal governing traffic into said first section and capable of displaying calling-on and yard indications, manually controlled means for causing said signal to display a calling-on indication when said first section is occupied by a train, and means operating automatically for causing said signal to display a yard indication when such train proceeds into said second section. 75
3. In combination, a stretch of railway track divided to form a series of sections, a signal governing traffic into the first section of said series and capable of displaying a plurality of progressively favorable proceed indications, manually controlled means for causing said signal to display a proceed indication least favorable in character when the first section of said series is occupied by a train, and means operating automatically for thereafter causing said signal to display proceed indications of progressively favorable character as such train proceeds through succeeding sections of said series. 80
4. In combination, a stretch of railway track divided to form two sections, a signal governing traffic into the first of said sections and capable of displaying calling-on, yard and caution indications, manually controlled means for causing said signal to display a calling-on indication when the first of said sections is occupied by a train, and means operating automatically for causing said signal to display a yard indication when said train proceeds through the second of said sections and a caution indication when said train departs from said second section. 85
5. In combination, a stretch of railway track divided to form a series of sections, a signal governing traffic into the first section of said series and capable of displaying calling-on, yard and caution indications, manually controlled means for causing said signal to display a calling-on indication when the first section of said series is occupied by a train, and means operating automatically for causing said signal to successively display 90

- 105
- 110
- 115
- 120
- 125
- 130

yard and caution indications as such train proceeds through succeeding sections of said series.

6. In combination, a stretch of railway track divided to form a series of sections, a signal governing traffic into the first section of said series and capable of displaying calling-on, yard and caution indications, manually controlled means for causing said signal to display a calling-on indication when the first section of said series is occupied by a train, and means operating automatically and independent of a previous operation of said manually controlled means for causing said signal to successively display yard and caution indications as such train proceeds through succeeding sections of said series.

7. In combination, a stretch of railway track divided to form a section A—B, a switch leading from said section into a yard track, a signal governing traffic through said switch and capable of giving a calling-on and a yard indication among others, manually controlled means for causing said signal to give the calling-on indication when section A—B is occupied by a train, and means operating automatically to cause said signal to change from the calling-on indication to the yard indication when such train leaves section A—B provided said switch is reversed to admit traffic into said yard.

8. In combination, a stretch of railway track divided to form sections A—B and B—C provided with track relays T^1 and T^2 respectively, a switch leading from section A—B into a yard track divided to form a section D—E which is provided with a track relay T^3 , a signal governing traffic through said switch, a manual lever for said switch having normal and reverse positions, a manual lever for said signal having normal and reverse positions, a repeater relay U energized when said switch lever is normal provided track relays T^1 and T^2 are closed and energized when said switch lever is reversed provided track relays T^1 and T^3 are closed, a relay M energized, when said switch lever is reversed provided track relay T^1 is closed and relay T^3 is open, a home relay and a yard relay and a calling-on relay for said signal, means for energizing said home relay when said signal lever is reversed provided said calling-on relay is open and relay U is closed, a manually operable normally open push button, means for energizing said calling-on relay when said signal lever is reversed and said push button is closed provided said relays U and M are open, means for subsequently keeping the calling-on relay energized as long as relay U and relay M remain open and the signal lever remains reversed, means operating when said calling-on relay is opened to energize said yard relay if relay M closes, and means for causing said signal to give a calling-on or a yard indication

according as said calling-on or said yard relay is closed.

9. In combination, a section of railway track, a switch leading from said section into a yard track, a manual lever for the control of said switch, a signal governing traffic through said switch, a relay M , means for energizing said relay requiring that said switch lever be reversed and that said section be unoccupied and that said yard track be occupied by a train, a yard indication relay and a calling-on relay, a signal lever and a normally open push button for controlling said signal, means operating when said signal lever is reversed, and when relay M is open and said push button is closed to energize said calling-on relay, means operating if relay M closes to energize said yard indication relay without necessitating the closing of said push button, and means for causing said signal to give a calling-on or a yard indication according as said calling-on or said yard relay is closed.

10. In combination, a stretch of railway track, a signal governing traffic through said stretch, a manual lever for the control of said signal, a relay M controlled by traffic conditions in advance of said signal, a home relay and a yard indication relay and a calling-on relay for said signal, a normally open push button for controlling said signal, means operating when said signal lever is reversed and said push button is closed to energize said calling-on relay provided relay M is open, means operating when relay M is closed to energize said yard indication relay without necessitating the closing of said push button, and means for selectively causing said signal to give calling-on and yard indications according as said calling-on or said yard relay is closed.

11. In combination, a stretch of railway track divided to form a section, a switch leading from said section into a yard track and capable of occupying normal and reverse positions, a signal governing traffic into said section and capable of displaying a calling-on and a yard indication, manually controlled means for causing said signal to display a calling-on indication when said section is occupied by a train, and means operating automatically when said switch occupies a normal position for causing said signal to display a yard indication when such train leaves said section.

12. In combination, a stretch of railway track divided to form a first and a second section, a switch leading from said first section into a yard track and capable of occupying normal and reverse positions, a signal governing traffic into said first section and capable of displaying calling-on and yard indications, manually controlled means for causing said signal to display a calling-on indication when said first section is occupied by a

train, and means operating automatically when said switch occupies a normal position for causing said signal to display a yard indication when such train proceeds into said second section.

13. In combination, a stretch of railway track divided to form a series of sections, a switch leading from one of said sections into a yard track and capable of occupying normal and reverse positions, a signal governing traffic into the first section of said series and capable of displaying a plurality of progressively favorable proceed indications, manually controlled means for causing said signal to display a proceed indication least favorable in character when the first section of said series is occupied by a train, and means operating automatically when said switch occupies normal and reverse positions for thereafter causing said signal to display proceed indications of progressively favorable character as such train proceeds through succeeding sections of said series.

14. In combination, a stretch of railway track divided to form two sections, a switch leading from one of said sections with a yard track and capable of occupying normal and reverse positions, a signal governing traffic into the first of said sections and capable of displaying calling-on, yard and caution indications, manually controlled means for causing said signal to display a calling-on indication when the first of said sections is occupied by a train, and means operating automatically when said switch occupies normal and reverse positions for causing said signal to display a yard indication when said train proceeds through the second of said sections and a caution indication when said train departs from said second section.

15. In combination, a stretch of railway track divided to form a series of sections, a switch leading from one of said sections into a yard track and capable of occupying normal and reverse positions, a signal governing traffic into the first section of said series and capable of displaying calling-on, yard and caution indications, manually controlled means for causing said signal to display a calling-on indication when the first section of said series is occupied by a train, and means operating automatically when said switch occupies normal and reverse positions for causing said signal to successively display yard and caution indications as such train proceeds through succeeding sections of said series.

16. In combination, a stretch of railway track divided to form a series of sections, a switch leading from one of said sections with a yard track and capable of occupying normal and reverse positions, a signal governing traffic into the first section of said series and capable of displaying calling-on, yard and caution indications, manually con-

trolled means for causing said signal to display a calling-on indication when the first section of said series is occupied by a train, and means operating automatically when said switch occupies normal and reverse positions and independent of a previous operation of said manually controlled means for causing said signal to successively display yard and caution indications as such train proceeds through succeeding sections of said series.

17. In combination, a stretch of railway track divided to form sections A—B and B—C, a switch leading from said sections into a yard track, a signal governing traffic through said stretch and capable of giving a calling-on and a yard indication among others, manually controlled means for causing said signal to give the calling-on indication when section A—B is occupied by a train, and means operating automatically to cause said signal to change from the calling-on indication to the yard indication when such train enters section B—C.

18. In combination, a section of railway track, a switch leading from said section into a yard track and capable of occupying normal and reverse positions, a manual lever for the control of said switch, a signal governing traffic through said switch, a relay M, means for energizing said relay requiring that said switch lever be reversed and that said section be unoccupied and that said yard track be occupied by a train, a yard indication relay and a calling-on relay, a signal lever and a normally open push button for controlling said signal, means operating when said signal lever is reversed, and when relay M is open and said push button is closed to energize said calling-on relay, means operating when said switch lever occupies normal and reverse positions if relay M closes to energize said yard indication relay without necessitating the closing of said push button, and means for causing said signal to give a calling-on or a yard indication according as said calling-on or said yard relay is closed.

19. In combination, a stretch of railway track, a signal governing traffic through said stretch, a switch leading from said stretch into a yard track and capable of occupying normal and reverse positions, a manual lever for the control of said signal, a relay M controlled by traffic conditions in advance of said signal, a home relay and a yard indication relay and a calling-on relay for said signal, a normally open push button for controlling said signal, means operating when said signal lever is reversed and said push button is closed to energize said calling-on relay provided relay M is open, means operating when said switch occupies normal and reverse positions and when relay M is closed to energize said yard indication relay.

without necessitating the closing of said push button, and means for selectively causing said signal to give calling-on and yard indications according as said calling-on or said yard relay is closed.

In testimony whereof we affix our signatures.
